UNITED STATES PATENT OFFICE.

JAMES RUNYEN AND DAVID RUNYEN, OF GRAND RAPIDS, MICHIGAN.

GREASE-CABINET.

1,215,313.

Specification of Letters Patent. Patented Feb. 6, 1917.

Application filed December 7, 1914. Serial No. 875,841.

To all whom it may concern:

Be it known that we, JAMES RUNYEN and DAVID RUNYEN, citizens of the United States of America, residing at Grand Rapids, in 5 the county of Kent and State of Michigan, have invented certain new and useful Improvements in Grease-Cabinets; and we do hereby declare the following to be a full, clear, and exact description of the invention, 10 such as will enable others skilled in the art to which it appertains to make and use the same.

This invention relates to a grease cabinet adapted to hold lubricating material of 15 heavy and viscous nature. It is the object and purpose of this invention to provide a device of this character and one in which the grease may be withdrawn in measured quantities therefrom without the operator 20 being under the necessity of coming in contact therewith, and to provide a pumping device in connection with a receptacle for containing the grease and associate therewith a single valve construction which will 25 act to prevent the return of the grease to the receptacle and force its discharge through an outlet, at the same time permitting the free withdrawal of grease to the pumping device. Various other objects and 30 purposes consisting in a specific construction of the valve, pump and receptacle will be apparent upon understanding being had of the embodiments of the invention shown in the accompanying drawings, in which:

35 Figure 1 is a side elevation with parts broken away and shown in section illustrating one type of the invention.

Fig. 2 is a vertical sectional view through the lower part of a modified form of structure; and

Fig. 3 illustrates in side elevation, with parts broken away and shown in section, a still further modification.

Like reference characters refer to like 45 parts throughout the several views of the drawings.

The receptacle for containing the grease may be in the form of a cylindrical can 1 provided with a cover 2 by means of which 50 the grease may be introduced into the can. Located along the side of the can is a pumping device consisting of a tube or barrel 3 having therein a plunger 4, the upper end

of which extends above the barrel 3, and provided with a handle 5 by means of which 55 the plunger may be given reciprocal movement. As shown in Fig. 1, the lower end of the tube 3 is threaded into a T-fitting 6, one end of which extends through a side of the can 1 and has connected therewith 60 an elbow 7, the other end of the fitting having similarly connected therewith an elbow 8 into which is inserted a coupling having connection with a flexible tubular outlet 9. A ball 10 is loosely seated in a seat 11 secured in the lower end of the elbow 7 and has limited movement with respect to said seat, a set screw 12 inserted in the upper part of the elbow being provided to limit 65 this movement as desired. Between the T-fitting 6 and elbow 8 an angular bracket member 13 is connected upon which the operator may place his foot to hold the device in place when the plunger 4 is drawn upwardly. 75

In operation the can 1 is wholly or partially filled with grease of viscous nature which may be removed on operation of the plunger 4. On the upward movement of 80 said plunger the ball 10 will be drawn against the set screw 12 leaving an opening for the entrance of the grease into the barrel 3 and on the downward stroke of the plunger, ball 10 will seat to close the opening, the grease thereupon being forced outward through the tube 9. It will be noted 85 in this connection that by reason of the relatively small interior diameter of the tube 9, on the upward stroke of the plunger the grease in the tube 9 will not be drawn into 90 the tube 3 because of the friction against the inner sides of said tube and the viscous nature of the grease but that it will be drawn from the can 1, there being required only a single valve 10 for the operation of the device without the necessity of any valve in the elbow 8 or tube 9, and it is also apparent that the tube 3 may be made to contain a specified or a measured quantity which 95 will be taken from the receptacle 1 on each upward stroke and discharged through the tube 9 with each downward stroke of the plunger.

In Fig. 2 a slight modification in detail is shown, the bottom of the receptacle having 100 connected therewith an outlet member 14

screw threaded into a casting 15 having an opening therethrough in the upper end of which the ball 16 similar to ball 10 is seated to form the valve required, this ball 16 being limited in its upward movement by the headed rod 17 as shown. A casting 18 is fastened to the casting 15 and the barrel 3 screw threaded therein as shown while also connected therewith by a screw threaded 10 connection is a hose coupling 19 with which the flexible tube 9 has connection, ways being provided in the casting 18 so that grease taken from the can 1 will be drawn into the barrel 3 and then forced outward through 15 the flexible outlet tube 9 in the same manner as described with reference to the construction shown in Fig. 1.

In Fig. 3 a still further modification is shown in which greases of very heavy consistency may be withdrawn and discharged from the receptacle. In this construction the lower end of the receptacle 1 is tapered for a short distance and terminates in a smaller cylindrical extension 20 with which the 20 grease outlet 14 is connected, it also being connected to a casting 15 having thereon a casting 18 formed substantially identical with the similar construction shown in Fig. 2. A plunger consisting of a rod 21 having 25 on its lower end a head 22 and at its upper end above the top 2 of the can an operating handle 23, is provided extending lengthwise of the receptacle 1. The operation is the same so far as the plunger 4 is concerned but 30 it is also designed that on the upward stroke of plunger 4 the handle 23 will be forced downwardly, forcing the heavy grease into the section 20 and outlet 14 so that there will be a force in addition to the suction exerted 35 by plunger 4 to transfer the grease to the barrel 3. By elevating the plunger in the receptacle 1 a quantity of grease may be gathered beneath the head 22 and forced in the restricted section 20 and by exerting 40 pressure on the handle 23 at the same time that plunger 4 is carried upwardly, the grease will be transferred more easily from the receptacle 1 to the tube 3 after which it may be forced out through the flexible tube 45 9 in the usual manner. The casting 15 in the modification shown in Figs. 2 and 3 may also have an extension 13^a to serve the same purpose as the bracket 13 heretofore described in connection with the apparatus 50 shown in Fig. 1.

Various other modifications in detail may be resorted to without departing from the invention which is defined in the appended claims, the invention covering all modifications in structure falling within the scope of 55 said claims.

We claim:—

1. In a device of the character described, 60 a receptacle having at its lower end a reduced cylindrical extension, a plunger

mounted in the receptacle having a head adapted to operate in said extension, an outlet member communicating with said extension, a pumping device communicating with the outlet member, a movable valve seated 70 between the pumping device and receptacle, and a flexible outlet tube of relatively great length and small inner sectional area also communicating with the outlet member and the pumping device, the valve also being 75 located between the outlet member and tube, substantially as described.

2. In a device of the character described, a receptacle having at its lower end a reduced cylindrical extension, a manually operable plunger mounted in the receptacle having a head adapted to operate in said extension, an outlet member communicating with the said extension, a casting having a passageway secured to the outlet member and 80 communicating therewith, a movable valve seated at the end of said passageway, a casting provided with two passageways secured above the first casting and valve, a pumping device and a flexible outlet tube of relatively 85 great length and small inner sectional area attached to said second casting and communicating with the said passageways therein, substantially as described.

3. In a device of the character described, 90 a receptacle having an open upper end, a removable cover for said open end, a barrel located outside and alongside the receptacle and secured thereto adjacent its upper end, a member having a passageway therein into 100 which the lower end of the barrel is threaded, the interior of the barrel communicating with the passageway, said member being secured to the receptacle and its passageway communicating with the interior of the receptacle, a movable valve interposed in the 105 passageway between the barrel and receptacle, a foot piece secured to said member, a flexible conduit connected to said member having a passage freely communicating with the passage in the member, there being a free and unobstructed passage between the barrel and said conduit, and a piston movably mounted in the barrel.

4. In a device of the character described, 115 a receptacle having means for the insertion of grease or the like therein, a barrel located outside and alongside of the receptacle, a member having a passageway therein into which the lower end of the barrel is passed 120 and secured, the interior of the barrel communicating with the passageway, said member being secured to the receptacle and its passageway communicating with the interior of the receptacle, a movable valve interposed in the passageway between the barrel and receptacle, a piston movably mounted in the barrel and having an operating member connected thereto extending above the barrel, a 125 foot member connected with the device, a 130

flexible conduit connected to the first mentioned member having a passage communicating with the passage in said member there being a passage between the barrel and
5 said conduit and a handle secured to the upper end of the operating member for the piston, substantially as described.

In testimony whereof we affix our signatures in presence of two witnesses.
